UNITED STATES PATENT OFFICE.

JACQUES REIMANN, OF BIRMINGHAM, ENGLAND, ASSIGNOR TO TUBES LIMITED, OF BIRMINGHAM, ENGLAND.

ROLLING MILL.

1,424,678.

Specification of Letters Patent. Patented Aug. 1, 1922.

Application filed June 2, 1920. Serial No. 386,087.

(GRANTED UNDER THE PROVISIONS OF THE ACT OF MARCH 3, 1921, 41 STAT. L., 1313.)

To all whom it may concern:

Be it known that I, JACQUES REIMANN, engineer, residing at Erdington, Birmingham, England, have invented certain new 5 and useful Improvements in Rolling Mills (for which I have filed application in England Feb. 11, 1919, Patent No. 135,707), of which the following is a specification.

This invention relates to rolling mills and 10 has for its object to provide improvements in the feeding mechanism as employed on the "pilgrim" or step-by-step type of rolling mill.

It is the object of the present invention 15 to provide means whereby the angular twist of substantially 90° imparted to the work between each "pass" can be obtained without difficulty at the start of the rolling operation, when the act of taking the preliminary "bites" results in a shorter travel of 20 the work than the normal, and thereby a proportionate reduction in the angle of twist of the work.

According to this invention the feed-spiral 25 comprises a plurality of sets of threads each of different pitch and engaged by a co-operating nut, and means are provided for operating selectively either one of the nuts to actuate the feed spiral. Thus two sets 30 of threads may be employed, one set of normal pitch, and the other of a shorter pitch for use when starting the work in the rolls. By employing more than two sets of threads the same feed-spiral may be employed for rolls of different diameter which 35 involve a greater or a lesser travel of the work, thus economizing in time in setting up the machine and reducing first cost of the parts thereof.

40 To economize space in the machine the different threads may be cut upon the same portion of the feed-spiral and may consequently intersect one another, and have the same, or opposite angles of inclination.

45 This allows the several nuts to be mounted closely adjacent to one another and thus reduces the length of the housing required to carry them.

The pawls may be in the form of plungers 50 radially disposed around the ratchet teeth on the nuts, and cams may be provided on members rotatable, manually or otherwise, around the nuts to lift the plungers against the action of springs, the mechanism being

so arranged that one nut only at a time can 55 be engaged by the pawls, a neutral position being provided in which all the pawls are disengaged from the nuts.

The manner of carrying out the invention is illustrated in the accompanying drawings, 60 in which—

Figure 1 is a central longitudinal section through the feed-spiral mechanism taken in the plane of its axis, and

Figure 2 is a transverse section of which 65 the left hand part is taken on the line 2, 2 of Figure 1, and the right hand part on the line 2^a, 2^a, also of Figure 1.

Fig. 3 is a diagrammatic view of the device. 70

Like letters indicate like parts throughout the drawings.

The feed-spiral comprises the usual multiple-threaded member A, with the threads A², but in addition to these has formed upon 75 it a second feed-spiral with threads A³ which intersect those of the first one and are of a shorter pitch. The usual housing B for the nut C which engages the first feed-spiral is lengthened to receive also the nut 80 C² for the second spiral. Each nut has on its periphery the usual ratchet teeth C³, and the pawls for each are in the form of radially disposed plungers D, pressed inwardly to the ratchet teeth by means of the springs 85 D². Three such pawls may be employed for each nut and each pawl has formed in its side a notch D³. A segment E of a ring mounted concentrically with the axis of the feed-spiral to move angularly about it, lies 90 against the plungers D and carries on the face adjacent to them a parti-annular projection E² which traverses their notches D³, clearance being provided in the latter for the radial movement of the plungers as they 95 ride over the ratchet teeth. Notches E³ are formed in the projection E² and upon their bottom surfaces E⁴ rest the outer sides of the notches D³ in the plungers D, when the latter are at their inner position radially. 100 One side E⁵ of each notch E³ in the projection E² is of wedge or cam form so that if the ring segment E is moved around the axis of the feed-spiral, the pawls D are lifted by their agency from the ratchet teeth C³ and the nut to which they belong becomes 105 inoperative. Similar ring segments E and projections E² are provided for the pawls

of each nut C, C² and are carried upon or integral with segments of bevel wheels E⁶ spaced opposite one another between the two nuts. A bevel pinion F mounted upon a 5 spindle F² rotatably supported in a cover B² for the housing B, gears with the bevel wheel segments E⁶ and can be rotated by means of a hand lever F³.

In operation, when the bevel pinion F is 10 rotated, the ring segments E are moved in directions opposite one another around the feed-spiral, the cam faces E⁵ at the sides of the notches in the projections E² being so arranged that in one extreme of movement one 15 set of pawls is in engagement with the ratchet teeth C³ of one nut, and at the other extreme the other set of pawls is engaged with the teeth of the other nut, an intermediate position being provided in which both 20 sets are disengaged, so that both nuts cannot be in operation at once.

At starting the operator puts into action the pawls which engage the shorter pitch spiral, and, when, during the operation of 25 rolling, the full travel is obtained, the longer pitch spiral is brought into engagement and the operations are then continued in the usual manner. If desired the change 30 from one feed to the other could be effected by connecting the above described mechanism with a moving part of the rolling mill.

By making the feed-spiral of sufficient diameter several sets of threads of different pitches can be formed thereon thus economizing 35 maintenance cost by reducing the number of separate feed-spirals stocked to suit the various diameters of rolls. Time occupied in changing spirals would thereby be reduced considerably.

40 Where more than two sets of spirals having different pitches are cut on the same feed member it might be desirable that some should be of opposite inclination to the others to avoid liability of fouling at the 45 groove-junctions in the nuts, but this forms no part of the present invention.

What I claim as my invention and desire to secure by Letters Patent of the United States is:—

50 1. In a rolling mill, a plurality of feed-spirals each of a different pitch and operatively connected to the work-carrier and travelling with it to cause its partial rotation, each feed spiral adapted to cause a 55 twist of substantially 90°, the longest pitch effecting this during the full return of the carrier, and the shorter pitches effecting it in lesser travels of the carrier, each feed spiral engaged by a co-operating nut immovable 60 endwise, and means operable selectively for holding any one nut against rotation during the retraction of the work-carrier and work, substantially as set forth.

65 2. In a rolling mill, two feed spirals axially mounted with the work-carrier and

travelling with it, each feed-spiral constituted by a quick-pitch threaded member, the pitch of one adapted to cause substantially 90° of twist of the carrier and work during its normal full travel, the pitch of the other 70 adapted to cause a similar degree of twist with a shorter travel of the work, a co-operating nut, immovable endwise, for each of said feed-spirals, a pawl for each nut engaging ratchet teeth thereon, and arranged to 75 permit rotation of either nut during the forward stroke of the carrier and to hold either stationary on the return movement thereof, and means for engaging selectively either pawl with its associated nut, substantially as 80 set forth.

3. In a rolling mill, a feed-spiral member coaxially mounted with the work-carrier, and travelling with it, two sets of threads upon said feed-spiral member, one set adapted to cause an angular twist of the carrier through substantially 90°, during the full travel of said carrier, the other adapted to cause a similar twist during a shorter travel of the carrier, each set of threads engaged by a co-operating nut, said nuts being situated adjacent one another and immovable endwise, the threads engaged by one nut extending over the part of the feed-spiral member carrying the threads engaged by the 95 other nut, pawls engaging ratchet teeth formed on the periphery of said nuts and arranged so that the nuts can rotate freely during the forward movement of the carrier, and either nut at will can be held against rotation during the return movement of the 100 carrier, cams engaging the pawls upon each nut, and gearing actuating said cams whereby at will one nut only at a time can be operatively engaged by its pawls, substantially 105 as set forth.

4. In a rolling mill as claimed in claim 3, the employment of radially disposed pawls, spring pressed into engagement with the ratchet teeth on each co-operating nut for 110 the several threads on the feed-spiral member, two sets of cams, each set carried upon members rotatable around the axis of the feed-spiral, one set of cams engaging the pawls of one co-operating nut, the other set 115 engaging those of the other nut, and a bevel pinion rotatable at will, engaging corresponding bevel teeth on each cam-carrying member, the several parts arranged in such manner that one set of pawls is completely 120 withdrawn from one nut, before the other set of pawls is released to engage the other nut, substantially as set forth.

In testimony whereof I have signed my name to this specification in the presence of 125 two subscribing witnesses.

JACQUES REIMANN.
